DRIVER-ADJUSTING MEANS FOR FASTENING-INSERTING MACHINES

Filed July 7, 1938

Fig.1.

UNITED STATES PATENT OFFICE

2,160,843

DRIVER-ADJUSTING MEANS FOR FASTEN-
ING-INSERTING MACHINESJohn A. Duran, Beverly, Mass., assignor to
United Shoe Machinery Corporation, Paterson,
N. J., a corporation of New Jersey

Application July 7, 1938, Serial No. 217,961

12 Claims. (Cl. 1—32)

In machines for inserting fastenings, as those by which nails are driven for attaching heels or heel-portions to shoes, the extent to which the drivers insert the nails is important and may call for variation as the character of the work changes. For example, in attaching rubber lifts or whole heels, the heads of the nails should reach points in the work which bear a definite relation to the washers or other reinforcing means molded in the rubber. If the nail-heads do not arrive at the reinforcement, the attachment will be insecure. If they are driven too deeply with respect to the washers, the heel will be distorted. If the reinforcement is in the form of a sheet of fabric, the heads may pass through it, and its effect be lost. Since the distance between the tread surfaces of the heels and their reinforcements differ for different makes and sizes, the operator of the heel-attaching machine is called upon to adjust the drivers upon their actuating member, so the extent of their projection into or through the nailing-die will vary. Means has heretofore been furnished for effecting such an adjustment, as by a wedge interposed between the actuating member and the plate carrying the drivers and movable and retained in its adjusted position by a screw. This, while accomplishing the desired end, is a comparatively slow and troublesome proceeding, and it is an object of the present invention to effect the adjustment of the drivers speedily and with little effort on the part of the operator.

In the attainment of the above object, I combine with such a reciprocatory driver-actuating member as the crosshead of a heel-attaching machine or other fastening-inserting apparatus and a plurality of drivers mounted upon such member, an adjusting member, movable through direct engagement by the operator, and a member engaging the adjusting member and also movable by the operator. By this direct movement of the adjusting member, the projection of the drivers from the actuating member into the co-operating die may be changed rapidly, until their relation is approximately correct, while by a more gradual movement of the second member, the final adjustment may be made to the slight additional extent required to give the exact location of the driver-ends sought. The adjusting member may be moved and locked for the first adjustment and then moved independently of the condition of the lock for the second adjustment. More specifically, the adjusting member is formed in relatively movable portions, one being herein shown as in the form of a wedge movable upon the crosshead,

and upon which the plate carrying the drivers rests, while the other portion consists of a toothed slide movable upon the wedge. The two portions may be adjusted together by a single movement of the operator's hand and locked in place by a detent or like retaining member, movable upon the crosshead. Then, by shifting the wedge, as by a screw threaded into said wedge and engaging the locked slide, a fine and accurate adjustment may quickly be made. The extent of these adjustments may be determined by indicating means, as by a scale carried by the wedge and visible outside the driver-plate.

In the accompanying drawing, Fig. 1 shows in perspective a particular embodiment of my invention, applied to a machine for attaching rubber lifts to heels;

Fig. 2 is a broken plan view of the driver-plate and more closely associated elements;

Fig. 3, a full vertical section on the line III—III of Fig. 2;

Fig. 4, a sectional detail corresponding to Fig. 3 but showing the locking member released, while in

Fig. 5 appears in section an example of the work done by the illustrated machine.

The apparatus in connection with which I have chosen to disclose this invention is similar to that of Letters Patent of the United States No. 1,365,802, Standish, January 18, 1921. Mounted for vertical reciprocation in the frame 10 of the machine is an upper crosshead 12 and a lower crosshead 14. The former crosshead is carried and guided by rods 16, and the latter by a spindle 18 and sleeves 20 surrounding the rods. In the crosshead 12 is mounted a nailing-die 22, with which is associated the lift- or heel-holder 24 of the previously mentioned patent, this being movable into and out of operating position above the die under the control of the usual loader-arm 26. Upward movement of the crosshead 12 serves to force a lift in the holder 24 against a heel-base attached to a shoe supported upon a jack, this jack not being included in the drawing. Movable in passages 28 in the die are nail-drivers 30, these being assembled in a group upon a plate 32. The plate with its drivers is reciprocated by the crosshead 14 to cause the insertion in the work of nails resting upon the upper ends of the drivers.

Since the crosshead 14 has a constant initial position and extent of travel, the depth to which the drivers sink the heads of the nails in the lift will depend upon the vertical position of the driver-assembly upon the crosshead. Variation in this position to meet the requirements of different reinforcements in the lifts, or other work-

conditions, is obtained in the following manner. The driver-plate 32 is received in ways 34, 34 formed at opposite sides of an adjusting wedge or slide 36, said plate resting upon a horizontal surface 38 of the wedge between the ways. The lower, upwardly and rearwardly inclined surface 40 of the wedge is carried upon a similarly inclined surface 42 of the crosshead 14. As the wedge is thrust rearwardly or drawn forwardly, its movement up or down the inclined surface 42 will cause the driver-assembly to be correspondingly raised or lowered. The adjustment thus obtained is releasably held by a detent 44 rising from a plunger 46 movable vertically in a bore in the crosshead 14 beneath the wedge-slide. The detent may enter between any two of a series of inclined teeth 48 carried by the wedge, said detent being forced up by expansion-springs 50, 50 beneath it. If the drivers are to be raised, the inclination of the rear faces of the teeth, which is toward the front of the machine, allows the movement of the wedge to be made without a special act on the part of the operator to release the detent. This is because the supplemental inclination of the forward face of the detent will cause it to be cammed down by the pressure of the teeth. If the drivers are to be lowered, the wedge is freed from the lock applied by the detent, through the action of a plunger 52, movable in a horizontal bore in the rear of the crosshead. The forward extremity of the plunger is reduced laterally to enter a slot 54 at the bottom of the detent-plunger 46. Upon the lower edge of this reduced portion is a cam-incline 56 which engages a pin 58 bridging the slot 54. Normally, the plunger 52 is urged rearwardly by an expansion-spring 60, surrounding it outside the crosshead, this being to an extent permitted by the engagement of its hooked forward end 62 with the pin 58. This leaves the detent free to assume its locking position. When the operator wishes to lower the drivers, he presses in the plunger 52, so its edge 56 depresses the detent. Thereupon, the released wedge may be drawn forward. Just after the detent 48 has been withdrawn from the teeth 48 by the cam, the forward end of the body of the plunger 52 contacts with the plunger 46, preventing excessive releasing movement of the former plunger. The travel 50 of the wedge in both directions may be limited by screws 63, 63, threaded oppositely into the ends of said wedge, with their heads projecting over the adjacent edges of the crosshead 14.

The movement of the wedge just described gives a very rapid adjustment, but with this alone, it might be difficult to locate the drivers at the exact height desired. An additional fine adjustment is therefore furnished. The locking teeth 48 are formed not as an integral part of the sliding wedge 36 but on a secondary sliding portion 64, which is movable upon the wedge. The under side of the wedge is slotted at 66 to receive the slide 64, and the two sliding elements are connected by a screw 68 threaded into the wedge 65 and having near its forward extremity a circumferential flange 70 entering a transverse groove 72 in the slide 64. When the screw 68 is rotated by a head or finger-piece 74, the wedge may be moved in or out, while the slide 64 remains locked to the crosshead by the detent 44. By this means, there may readily be obtained a precise final adjustment, if that given by the movement of the compound slide 36, 64 was not correct. The screw 68 may be retained in the position to which 75 it has been turned, by a spring-detent 76 at-

tached to the under side of the slide 64 and entering any one of a series of depressions 78 formed about the periphery of the flange 70.

To relieve the operator of the necessity for making measurements of the location of the upper ends of the drivers, indicating means is provided. This is shown as a scale 80 lying in a depression in the upper face of the wedge 36 near one side and having inscribed upon its upper surface graduations 82, which may correspond to lifts or heels of different characters. These graduations may be referred to some index-line, as that furnished by the forward edge 84 of the driver-plate 32. Each numbered graduation may correspond to driver-adjustments of one-thirty-second of an inch, and also to the successive steps of the coarse adjustments furnished by the teeth 48. The intermediate unnumbered graduations may represent variations of one-sixty-fourth of an inch, attained by rotation of the screw 68. To furnish a preliminary adjustment of the scale with respect to its index-line, the former is shown as variable in position upon the wedge by a slot-and-screw connection 86.

An example of the work in connection with which the present invention is of especial utility is illustrated in Fig. 5 of the drawing. Here, a heel-base H has been attached to a shoe, and to this a rubber lift L has been secured by nails, one of which appears at N, these nails having 30 their heads driven into full engagement with washers W molded into the lift. By the adjustments of the driver-assembly hereinbefore described, the relation of the nail-heads to the washers may be accurately established for this or 35 similar work, with the expenditure of a minimum of time and effort by the operator.

Having described my invention, what I claim as new and desire to secure by Letters Patent of the United States is:

1. In a fastening-inserting machine, a reciprocatory actuating member, a plurality of fastening-drivers mounted upon the actuating member, an adjusting member movable through direct engagement by the operator to effect a relatively 45 rapid change in the projection of the drivers from the actuating member, and a member engaging the adjusting member and movable by the operator to effect a more gradual change in the projection of the drivers.

2. In a fastening-inserting machine, a reciprocatory actuating member, a plurality of fastening-drivers mounted upon the actuating member, an adjusting member movable upon the actuating member to vary the projection of the drivers 55 therefrom, means for locking the adjusting member upon the actuating member or for releasing it for movement, and means acting independently of the condition of the locking means for moving the adjusting member.

3. In a fastening-inserting machine, a reciprocatory actuating member, a plurality of fastening-drivers mounted upon the actuating member, an adjusting member movable upon the actuating member to vary the projection of the drivers 65 therefrom, said adjusting member having relatively movable portions, means for releasably locking one of the portions of the adjusting member to the actuating member, and means arranged to move portions of the adjusting member 70 relatively to each other.

4. In a fastening-inserting machine, a reciprocatory actuating member, a plurality of fastening-drivers mounted upon the actuating member, an adjusting member movable upon the actuating 75

member to vary the projection of the drivers therefrom, said adjusting member having relatively movable portions, means for releasably locking one of the portions of the adjusting member to the actuating member, means arranged to move portions of the adjusting member relatively to each other, and indicating means by which the extent of movement of the adjusting means for work of different characters may be determined.

5 5. In a heel-attaching machine, a nailing-die, drivers movable therein, a plate upon which the drivers are mounted, a reciprocating crosshead carrying the plate, an adjusting member interposed between the crosshead and the plate and having relatively movable portions, said adjusting member being arranged for movement of its portions together by the operator to effect a comparatively rapid change in the projection of the drivers into the die, and means arranged to produce the relative movement of the portions of the member to change more gradually the projection of the drivers into the die.

10 6. In a heel-attaching machine, a nailing-die, drivers movable therein, a plate upon which the drivers are mounted, a reciprocating crosshead carrying the plate, a driver-adjusting member interposed between the crosshead and the plate, said adjusting member having two portions, means for releasably locking one of the portions 15 to the crosshead, and means arranged to produce relative movement between said portions.

20 7. In a heel-attaching machine, a reciprocating crosshead, a driver-plate carried thereby, an adjusting slide movable upon the crosshead and upon which the driver-plate rests, a locking 25 slide movable upon the adjusting slide, a movable locking member connecting the locking slide to the crosshead, and means arranged to produce relative movement between the slides.

25 8. In a heel-attaching machine, a reciprocating crosshead, a driver-plate carried thereby, an adjusting slide movable upon the crosshead and upon which the driver-plate rests, a locking slide 30 movable upon the adjusting slide, a movable locking member connecting the locking slide to

the crosshead, means movable upon the crosshead for releasing the lock, and means arranged to produce relative movement between the slides.

35 9. In a heel-attaching machine, a reciprocating crosshead, a driver-plate carried thereby, a wedge-slide movable upon the crosshead and upon which the driver-plate rests, a toothed slide movable upon the wedge, a detent movable upon the crosshead and engaging the teeth of the slide, and a screw threaded into one of the slides and 10 engaging the other.

40 10. In a heel-attaching machine, a reciprocating crosshead, a driver-plate carried thereby, a wedge-slide movable upon the crosshead and upon which the driver-plate rests, a scale carried by the wedge and being visible outside the driver-slide, a toothed slide movable upon the wedge, a detent movable upon the crosshead and engaging the teeth of the slide, and a screw threaded into one of the slides and 15 engaging the other.

45 11. In a heel-attaching machine, a reciprocating crosshead, a driver-plate carried thereby, a wedge-slide movable upon the crosshead and upon which the driver-plate rests, a toothed slide 20 movable upon the wedge, a spring-actuated detent movable upon the crosshead and engaging the teeth of the slide, a releasing member movable upon the crosshead and provided with a cam-surface acting upon the detent, and means 25 acting upon the slides to move them relatively to each other.

50 12. In a heel-attaching machine, a reciprocating crosshead, a driver plate carried thereby, a wedge-slide movable upon the crosshead and up- 35 on which the driver-plate rests, a toothed slide movable upon the wedge, a detent movable upon the crosshead and engaging the teeth of the slide, a spring-actuated plunger movable upon the crosshead, said plunger having a portion acting 40 upon the detent to retain the two in co-operation and a portion acting upon the detent to separate it from the teeth, and a screw threaded into one of the slides and engaging the other.

JOHN A. DURAN. 45
